UNITED STATES PATENT OFFICE.

PERCY C. SMITH, OF EAST ORANGE, NEW JERSEY, ASSIGNOR TO WESTERN ELECTRIC COMPANY, INCORPORATED, OF NEW YORK, N. Y., A CORPORATION OF NEW YORK.

MEASURED-SERVICE AUTOMATIC TELEPHONE SYSTEM.

Application filed June 20, 1922. Serial No. 569,700.

To all whom it may concern:

Be it known that I, PERCY CLAYTON SMITH, a citizen of the United States of America, residing at East Orange, in the 5 county of Essex, State of New Jersey, have invented certain new and useful Improvements in Measured-Service Automatic Telephone Systems, of which the following is a full, clear, concise, and exact description.

10 This invention relates to automatic telephone systems and more specifically to a metering circuit arrangement for systems of this character.

The object of the invention is to provide 15 an improved circuit arrangement for automatically operating the calling line meter on ordinary calls upon the completion of the connection, and for preventing the operation of the calling line meter on so-called 20 free calls; that is, on calls to officials of the telephone company, the police or fire departments, etc.

In accordance with this invention, these 25 free lines are grouped in a certain level or levels of the connector and the connector is provided with means, actuated only when the connector is set on said levels, to supply current to the calling line without affecting a circuit change in the calling line to cause 30 the meter to record the call, but if such connector is set on any other level, in connecting with an ordinary line, this means is not rendered active and current is supplied 35 to the calling line and a circuit change is simultaneously brought about in the calling line circuit to cause the meter to record the call.

Referring to the drawings, Fig. 1 shows 40 a subscriber's line, a primary line switch, a secondary line switch, a connector and a called subscriber's line; and Fig. 2 shows a modified form of the invention.

Only so much of the circuits are shown as 45 is necessary to comprehend the invention. Complete circuits of the primary and secondary line switches are shown in Wicks Patent No. 1,379,068, issued May 24, 1921.

It is thought that the invention will be 50 most clearly understood from a detailed description of the operation of the system.

When a subscriber at substation A removes his receiver to initiate a call, circuits are closed to operate the primary and secondary line switches C and D as described 55 in the said Wicks patent to extend the call-

ing line to the connector H. It will be understood that a number of selectors may be, and in practice are, inserted between the secondary line switch D and the connector H. These selectors are shown in detail in 60 the said Wicks patent and need not, therefore, be described herein. Upon the extension of the calling line to the connector, the impulse relay 1 operates, energizing the usual first slow relay 2 which grounds the release 65 trunk 3 leading back to the primary and secondary line switches to hold them set, and prepares a circuit for the connector vertical magnet 4. The impulse relay now responds to the tens series of impulses from the sender 70 S at the calling substation and controls the vertical magnet 4 in series with slow relay 5 to set the connector wipers 6 to the desired level of contacts in which are located the contacts to which the called line is connect- 75 ed. We will assume that in this instance, the called line is not a free line. After this series of impulses, slow relay 5 releases to 80 prepare the circuit for the rotary magnet 7 and the slow relay 8 through the now 85 operated off-normal switch 9. When impulse relay 1 is operated for the units impulses from the sender S, the rotary magnet 7 is operated to step the wipers to the contacts of the desired line, and slow to re- 90 lease relay 8 energizes and remains energized for a short interval after the wipers reach the called line terminals. If the called line is busy, a ground will be present on the test conductor 10 thereof and a circuit will 95 be closed through an alternate contact of relay 8 for the busy relay 11 which will lock up and transmit a busy signal from the busy tone source 12. If the called line is idle 100 relay 11 will not be energized since no ground is present on the test multiple 10 of the called line and as soon as the slow relay 8 releases after the line relay 1 re- 105 mains energized, a circuit is closed for the upper winding of relay 13 in series with the cut-off winding 14 of the line switch of the called line. Relay 13 and said cut-off winding energize in series. Relay 13 is constructed to attract its armature 61 before its other armatures, and at armature 61 locks 110 to grounded conductor 36. This is a well known construction. Relay 13 disconnects the rotary magnet 7 to prevent further operation thereof, grounds the called line terminal 10, and cuts the called line through 110

to the ringing circuit which leads from a normal contact of relay 15 and includes one winding of said relay and battery, so that when the called party responds to the signal he closes an operating circuit of relay 15 which cuts off the ringing circuit and extends the called line to the winding of the back bridge or reversing relay 16. Relay 16 therefore energizes in series with the called line circuit and operates to reverse the connection of the impulse relay 1 with regard to the calling line circuit. This reversal operates the polarized relay 17 in the lower talking conductor. The polarized relay will energize and close the circuit of the meter magnet 18 which thereupon locks up to the release conductor 19 now grounded at the inner right armature and alternate contact of the slow relay 2. The meter 18 locks up in order to prevent a second charge being made for the same call due to a possible accidental reoperation of the polarized relay 17. A non-inductive winding 20 in shunt of the polarized relay 17 provides a free path for voice current.

The circuits just traced in brief are well known as shown in the said Wicks patent. Reference will now be made to the circuits and apparatus by which applicant's object is achieved. Assuming now, that a free line is called, this line will be located in a certain level of the connector switch H having a segment 21 individual thereto located in an auxiliary bank over which a brush 22 attached to the connector shaft comes to rest at the end of the vertical movement of the connector. This results in the closure of a circuit for a relay 23. The mechanical arrangement of this switch is such that the brush 22 does not partake of the rotary movement of the connector. The connector is then set on the called line as described and the line is signaled. When the called party removes his receiver and relay 15 operates as described, talking current is applied to the called line circuit through relay 23. When relay 23 operated, it disconnected the back bridge relay 16 from the trunk conductors 24 and 25 and consequently said relay 23 does not operate to reverse the current in the calling line upon the response of the called subscriber as in the case of the former call which was charged.

Upon the termination of the conversation and the restoration of the receiver by the calling party, relay 1 releases. The release of this relay opens the circuit of the slow relay 2 and the inert condition of relays 1, 2 and 16 closes the following circuit for the release magnet 26 of the connector: battery, 26, 27, 28, 29, 30, 31, 32, 33 and 34 to ground. The connector brush shaft in restoring also restores the auxiliary brush 22 into connection with normal segment 35 which unlocks relay 23. The retraction of the inner right

armature of slow relay 2 removes ground from the trunk release conductor 3, leading back to the primary and secondary line switches C and D, respectively, releasing the same as described in the said Wicks patent. The retraction of the outer right armature of the slow relay 2 removes ground from conductor 36, thus releasing the locked up relays 15 and 13. The apparatus is now restored to its normal condition.

Referring now to the modification shown in Fig. 2, instead of providing a relay which operates at the end of the vertical movement to disconnect the back bridge relay and substitute itself as in Fig. 1, a relay 37 is provided to operate in parallel with the upper winding of the back bridge relay 38 and in series with the lower winding thereof upon the response of the called party. Although the relay 38 operates on a call that is to be charged to reverse the direction of current flow in the calling line to operate the polarized relay 39 to in turn operate the meter magnet 40 as described in Fig. 1, if a free level is selected by the connector brushes 41, (Fig. 2) the auxiliary brush 42 carried by the connector brush shaft in this case rests upon a segment 43 individual to this free level so that when the called subscriber removes his receiver, relay 37 operates. The circuit of relay 37 is as follows; battery 37, 44, 43, 42, 45, 46, 47, through the called line loop, 48, 49, 50, 51, lower winding of 38, 52, 53, 54, 55, 56, and 57 to ground. The upper winding of relay 38 is connected to the lower talking conductor 45, the return being through its lower winding to ground as traced. Relay 37 nullifies the effect of the current reversal caused by the back bridge relay 38, and in attracting its right armature locks up to the grounded conductor 55. This simultaneous operation of relays 37 and 38 will prevent reversing the direction of the current flowing in the calling line and thus prevent the operation of the polarized relay 39 and consequently this call will not be charged. The other circuits shown in Fig. 2 are identical with those shown in Fig. 1 and need not therefore be described.

What is claimed is:

1. In a telephone system, calling and called telephone lines, an automatic switch for interconnecting the same wherein said called lines terminate in groups, meters for said calling lines, a relay included in said switch responsive to the removal of the receiver of the called line for supplying current to the calling line of the proper character for operating the calling line meter, another relay, means for operating the same when any one of certain predetermined groups is selected by said automatic switch whereby said first mentioned relay is prevented from responding to the removal of

the receiver of the called line, and means for supplying talking current to the calling line.

2. In a telephone system, calling and called telephone lines, an automatic switch 5 for interconnecting the same wherein the called lines terminate in different levels, meters for the calling lines, means in the switch including a relay responsive to the removal of the receiver of any called line 10 reached by way of certain predetermined levels for supplying the talking current to the calling line in the proper direction to operate the calling line meter, another relay, means for operating the same when the called line is reached over any other level of the automatic switch whereby said first mentioned relay is prevented from responding to the removal of the receiver of the called line, and means for supplying the talking 15 current to the calling line in such a direction as not to cause the operation of said meter.

3. In a telephone system, calling and called telephone lines, an automatic switch 25 for interconnecting the same wherein said called lines terminate in groups, meters for said lines, means in the switch including a relay responsive to the removal of the receiver of any called line in certain of said 30 groups for operating the meter associated with the calling line, a second relay, means included in said automatic switch for operating the same when the called line is in any other group whereby the first mentioned relay is disabled, and means for supplying talking current to the called line.
4. In a telephone system, calling and called telephone lines, an automatic switch 35 for interconnecting the same wherein said called lines terminate in groups, meters for said lines, means in the switch including a relay responsive to the removal of the receiver of any called line in certain of said

groups for operating the meter associated with the calling line, a second relay, means 45 included in said automatic switch for operating the same when the called line is in any other group whereby the first mentioned relay is disabled, and means for supplying talking current to the called line through 50 the windings of said second relay.

5. In a telephone system, calling and called telephone lines, an automatic switch having a primary and a secondary movement for interconnecting the same wherein 55 said called lines terminate in different levels, meters for said calling lines, means in said switch responsive to the removal of the receiver of the called line for operating the calling line meter, a commutator, a brush therefor, means responsive to the primary 60 movement of said switch for moving said brush over said commutator, a circuit extended via said commutator and brush on certain switch levels, and means responsive 65 to the closing of said circuit for rendering said meter operating means inoperative.

6. In a telephone system, calling and called telephone lines, automatic switches for interconnecting the same including a 70 connector wherein said called lines terminate in levels, meters for said calling lines, means in said connector responsive to the removal of the receiver of the called line for causing the operation of the calling line 75 meter, a row of terminals in said connector, a brush arranged to engage any terminal in said row, a relay, means including said brush and any desired terminal for operating said relay, and means responsive to 80 the operation of said relay for rendering said meter operating means inoperative.

In witness whereof, I hereunto subscribe my name this 19th day of June A. D., 1922.

PERCY C. SMITH.
